UNITED STATES PATENT OFFICE.

LEO NIELSEN, OF LOGAN, UTAH, ASSIGNOR TO JOHN A. HENDRICKSON, OF SAME PLACE.

COMPUTING ATTACHMENT FOR PUMPS.

SPECIFICATION forming part of Letters Patent No. 667,452, dated February 5, 1901.

Application filed September 8, 1900. Serial No. 29,374. (No model.)

To all whom it may concern:

Be it known that I, LEO NIELSEN, a citizen of the United States, residing at Logan, in the county of Cache and State of Utah, have 5 invented certain new and useful Improvements in Computing Attachments for Oil-Dispensing Pumps; and I do hereby declare the following to be a full, clear, and exact description of the invention, such as will enable others skilled in the art to which it appertains to 10 make and use the same.

This invention relates to dispensing-pumps, and particularly to a computing attachment for such pumps.

15 The invention consists of a novel and peculiar scale-plate fixed to and standing vertically above the top of the pump and a price strip or band slidable over the plate and fixed to the top end of the pump-rod, so that every 20 movement of the pump-rod will be imparted to the price-band and move it vertically over the face of the plate.

25 In the accompanying drawings, forming part of this application, Figure 1 is a perspective view of the upper portion of a pump with my attachment applied thereto. Fig. 2 is a front elevation of the scale-plate. Fig. 3 is front elevation of the price strip or band. Fig. 4 is a perspective view of the strip or 30 band looking at its rear side. Fig. 5 is a similar view of a modification.

The same numeral references denote the same parts throughout the several views of the drawings.

35 The pump-head 1 has the usual discharge-nozzle 2, and the pump-rod 3 works through the head and has a toothed rack 4, engaged by a suitable pinion operated by a crank-handle 5, to operate said rod in a pump-cylinder below the floor 6. To the top of the head 1 is secured the flange 7 of the computing scale-plate 8, (hereinafter to be more fully described,) so that the latter will stand vertically from the head in front of the pump-rod. 40

45 The price strip or band 9 (described in detail later) is arranged to encompass the scale-plate and is carried by the top end of the pump-rod.

The price computing and measuring device 50 consists of the solid or imperforate plate 8, (preferably of sheet metal with white enamel,

front face,) having a column 10, which indicates gallons, quarts, and pints, an adjacent column 11 indicating gills, and a series of vertical lines 12, which divide the face into a series 55 of equal spaces, each space being equally divided by horizontal lines 13, which form gages for the band 8 to work to. The lines 12 and 13 form a series of intervals 14, each of which is occupied by numerals, which indicate the 60 price per gallon and fraction thereof and the quantity pumped when the top edge of the price-band 8 reaches the mark in either of the said columns desired, the whole surface of the plate being uninterruptedly occupied, 65 as above noted. Said device is completed by the band 9, preferably of the same material and finish as the plate, and is bent to encompass the plate, the ends thereof being secured together, and upon its rear side is formed a 70 sleeve 15 to fit the top end of the pump-rod, where it is secured by a set-screw 16. The front of the band is provided with a series of lines 17, which register at all times with the lines 12, and in the space between the lines 75 17 are numerals indicating the price from five cents to one dollar.

Referring to Fig. 5, the price-band 9^a has overlapping curved ends 18, forming a sleeve 15^a, by means of which and a set-screw 16^a 80 the band is attached to the pump-rod.

It is obvious that the price-band is pumped to the mark in the columns to dispense the quantity of liquid desired, and the price of said quantity is indicated by the numeral 85 first above the figure on the price-band at which the liquid is selling per gallon. For example, if oil is selling at forty cents per gallon and a purchaser wants five gills the first numeral above the "40" on the band 90 will be "7" after the band has been moved up to the five-gill mark in the column by pumping out five gills, the price of the latter therefore being seven cents.

In attaching the device to a pump the plate 95 is easily secured through its flange by suitable screws or rivets to the pump-head, the price-band readily slipped over the top of the plate, and the sleeve over the top end of the pump-rod, or the modified band may be bent 100 around the plate and its curved ends lapped over the pump-rod. In either case the said

rod is in the rear of the plate and band, so that there is no obstruction of the view of the numerals.

Having thus described my invention, what 5 I claim as new, and desire to secure by Letters Patent, is—

The combination, with the plate having a flange adapted to be secured to a pump, and provided with uninterrupted graduation- 10 marks, of the strip or band surrounding the plate and having price-marks and slid able

over the plate, and the sleeve on the band in the rear of the said plate adapted to engage a pump-rod to impart the motion of the rod to the band.

In testimony whereof I affix my signature in presence of two witnesses.

LEO NIELSEN.
